UNITED STATES PATENT OFFICE.

ALMERIAN A. DAVIS, OF HAMMOND, INDIANA.

CAR-DOOR.

No. 927,332.

Specification of Letters Patent.

Patented July 6, 1909.

Application filed February 4, 1909. Serial No. 476,143.

To all whom it may concern:

Be it known that I, ALMERIAN A. DAVIS, a citizen of the United States, residing at Hammond, in the county of Lake and State of Indiana, have invented new and useful Improvements in Car-Doors, of which the following is a specification.

My invention relates to improvements in car doors and car door hanging devices, particularly with reference to car doors such as are used on double deck stock cars employed for transporting hogs, sheep and other small animals and the said invention consists in the construction, combination and arrangement 15 of devices hereinafter described and claimed.

The object of my invention is to provide car doors of the class indicated with means for hanging such car doors so that either the upper or lower door may be moved to open or 20 closed position independently of the other, a further object being to provide cheap, simple, strong and durable means for hanging such car doors and permitting them to be readily opened and closed.

25 In the accompanying drawings:—Figure 1 is an elevation of a portion of a double deck stock car provided with door and door hanging devices constructed in accordance with my invention. Fig. 2 is a detail perspective 30 view of the hanger or guard element which is provided with an offset to clear the intermediate track and the hangers of the other door.

In accordance with my invention, the car 35 on which the upper and lower doors 1, 2, are employed, is provided with an upper track member 3, an intermediate track member 4 and a lower track member 5. The intermediate track member extends beyond each side of the door-ways or openings 6, a distance slightly greater than the width of such 40 door-ways. At the ends of said intermediate track members and spacing the same suitably from the wall of the car are brackets 7 which support such intermediate track 45 member and also form stops at the ends thereof. The upper track member 3 which is above the upper door-way extends a sufficient distance beyond one side of said door-way to enable the door 1 which is suspended 50 from said track member to clear said door-way. The lower track member 5 which is below the lower door-way extends a corresponding distance from the opposite side thereof so that the upper door must be

55 moved in one direction in order to open it and the lower door must in order to open it be moved in the reverse direction.

The upper and lower doors are provided at their upper corners with hangers 8, the upper ends of which project above the upper 60 sides of the doors and are provided with openings through which the upper and intermediate track members extend so that said upper and lower doors are respectively suspended from said upper and intermediate 65 track members. The lower door is also provided at its lower corners with similar hangers 9 which operate on the lower track member. The upper door has at its lower outer corner a similar hanger 10 which operates 70 on the intermediate track member. At the inner lower corner of said upper door is a guard member 11, which as shown in detail in Fig. 2, comprises an upper portion 12 which bears on the outer side of the door 75 80 and may be secured thereto as by means of screws and has at the lower edge of the upper door a laterally inwardly extending portion 13 from the inner side of which depends an offset guard arm or stop 14 which by reason of the portion 13 is disposed within the plane of the upper hangers of the lower door so that said guard arm clears said upper 85 hangers of the lower door and enables the upper and lower doors to be operated independently of each other. The said stop or guard arm as will be noted upon reference to Fig. 1 of the drawings extends below the intermediate track members as well as between the same and the approximate wall of 90 the car or other structure so that said stop arm prevents the lower inner corner of the upper door from moving outwardly from the side of the stock car since it will be caused to come in contact with the intermediate track 95 member as soon as the lower inner corner of the track door has been moved outwardly for a slight distance.

The usual stop strips against which the door closes are indicated at 15 on opposite 100 sides of the upper and lower door-ways and the doors are shown as provided with handles 16 to facilitate their being opened and closed and with hasps 17 for engagement with staples 18 on the stop strips to enable 105 the doors to be locked in closed position.

It will be understood from the foregoing description and by reference to the drawings

that the intermediate track member is common to the upper and lower doors so that a considerable economy is effected.

What is claimed is:—

- 5 A structure having an upper, intermediate and lower guiding and supporting track elements, disposed in parallel relation, upper and lower doors disposed respectively between the upper, lower and intermediate track elements, and each having hangers engaging two of said track elements, one of said doors also having a guard member provided with a lateral portion to clear the intermediate track element and the hangers
- 10

of the other door, and also provided with an offset stop extending between the side of the structure and the intermediate track element and those hanger members of the other door which engage said intermediate track element, said stop clearing said intermediate track element and the last mentioned hangers of the other door.

In testimony whereof I affix my signature in presence of two witnesses.

ALMERIAN A. DAVIS.
